UNITED STATES PATENT OFFICE.

ORNE H. TORGERSEN, OF CHICAGO, ILLINOIS, ASSIGNOR OF ONE-HALF TO FRANK A. B.
HOLMES, OF CHICAGO, ILLINOIS.

ELECTRIC CONTROLLER.

1,267,714.

Specification of Letters Patent. Patented May 28, 1918.

Application filed June 11, 1917. Serial No. 173,989.

To all whom it may concern:

Be it known that I, ORNE H. TORGERSEN, a citizen of the United States of America, and a resident of Chicago, in the county of 5 Cook, State of Illinois, have invented certain new and useful Improvements in Electric Controllers, of which the following is a specification.

This invention relates more especially to 10 that type of electrical controlling mechanisms for compressed air apparatus, in which the attainment of a predetermined high pressure in the storage reservoir will automatically open the electric circuit of the 15 operating motor, and in which with a subsequent reduction of the pressure in said reservoir to a predetermined low pressure will automatically close said circuit of the motor. And the present improvement has 20 for its various objects:

To provide a structural formation and combination of parts whereby rapid final opening and closing movements of the controlling switch of the electric motor is attained in a simple and efficient manner.

To provide a structural formation and arrangement of the operating spring of the switch mechanism, by which the final opening and closing movements of the controlling 25 switch is effected in a powerful and effective manner. All as will hereinafter more fully appear.

In the accompanying drawings:—

Figure 1, is a plan view of the mechanism. 35 Fig. 2, is a side elevation with parts in section.

Fig. 3, is a detail sectional elevation illustrating the application of the present mechanism to the direct operation of a relief 40 valve associated with the storage reservoir of a compressed air system.

Similar reference numerals indicate like parts in the several views.

Referring to the drawings, 1 designates 45 a fixed supporting frame adapted to support in associated relation the electric switch mechanism and pneumatic motor by which said switch mechanism is automatically operated.

2 designates an electric switch, preferably 50 of the ordinary jack knife type, mounted in an insulated manner on a horizontal extension or bracket 3 of the frame 1, and having the usual pivoted contact blade 4, as 55 shown.

5 designates an operating link pivoted to a vertical centrally arranged post or standard 6 on the main frame, with the free end of said link having a slotted formation for operative engagement with a transverse pin 60 7 carried by the free end of the pivoted contact blade 4 aforesaid.

8 designates an adjustable abutment screw carried by an overhanging portion of the post 6 aforesaid, and adapted to limit the 65 degree of upward movement of the operating link 5 aforesaid.

9 designates a primary toggle link pivoted to the post 6 in adjacent relation to the operating link 5 aforesaid. The pivot axis of 70 the respective links are preferably arranged in a horizontal plane as shown. Said primary toggle 9 extends in a direction away from the operating link 5 and intermediate of its length is formed with a rounded bearing head 10 for operative engagement with the hereinafter described abutment collar of the pneumatic motor of the mechanism.

11 designates a secondary toggle link or member, of a U shape, and pivoted by means 80 of its side arms to vertical side standards 12 of the main frame, with the pivot axis preferably in a plane cutting the vertical axis of the hereinafter described motor of the mechanism, and with said axis preferably on 85 a horizontal plane cutting the pivot axes of the operating link 5 and primary toggle link 9 aforesaid. Said secondary toggle link 11 is formed with a transverse head 13 at its free end, and such head is in turn formed 90 with an orifice adapted to receive the operating link 5 aforesaid, and have operative engagement therewith. The said orifice is made of greater height than the vertical thickness of the link 5, so that limited independent movement of the secondary toggle link 11 in either direction, may take place, before operative engagement with the link 5 is attained.

14 designates an abutment toe pivoted to 100 the transverse head 13 aforesaid, and 15 designates an adjusting screw adapted to move said abutment toe to and from the link 5 to vary the amount of the above described independent movement between the parts. 105

16 designates an elliptical spring, preferably formed of rod metal, and which at its respective ends has engagement with lateral pins or studs 17, 17 arranged near the outer or free ends of the respective primary and 110

secondary toggle links 9 and 11, aforesaid. With the described arrangement of said toggle links, as the primary toggle link 9 is moved to a position in which the respective 5 studs 17, 17 and the pivot axis of said primary toggle link are on a straight line, the said spring 16 is drawn out and elongated against the normal resiliency of the spring, so that as the free end of the primary toggle 10 link 9 is moved a short distance beyond said straight line, the spring will act to complete the movement of the two toggle links 9, 11 in a rapid and forcible manner, and in so doing will cause a very rapid and efficient opening 15 or closing of the switch 2, in accordance with the direction in which the mechanism is operated.

18 designates the casing of the pneumatic motor above referred to, fixedly associated 20 with the frame 1, and preferably comprising a pair of cup-shaped sections between which a piston diaphragm 19 is secured in any usual manner.

20 designates a vertical stem or post fixed 25 at its lower end in the upper section of the motor casing 18 aforesaid, and having its upper end screw threaded for the reception of the adjusting nut 21 of the upper abutment collar 22 of the mechanism.

23 designates the lower abutment collar 30 sliding upon the vertical post 20 and formed with a peripheral groove for operative engagement with the circularly enlarged head 10 of the primary toggle link 9 heretofore 35 described. Said lower abutment collar 23 also has operative engagement with the piston diaphragm 19 by means of a circular bearing head or disk 24 resting on the upper surface of said diaphragm and provided 40 with a series of studs 25 extending through orifices in the upper section of the motor casing 18 and having bearing engagement beneath said lower abutment collar 23 to effect an upward movement of the same in unison with that of said piston diaphragm 19.

26 designates a spring, preferably of the spiral compression type shown, arranged to encircle the vertical post 20, with its respective ends abutting against the upper and 50 lower abutment collars 22, 23 aforesaid. The tension of said spring 26, is capable of adjustment by the adjusting nut 21, in order that said spring will operate at any predetermined pressure beneath the piston dia- 55 phragm 19, to cause the initial movements of the mechanism heretofore described, in either direction.

While the present mechanism is primarily intended for electric switch opening and 60 closing operations in connection with compressed air apparatus, the invention is capable of application to said compressed air apparatus in other ways, and as illustrative of such different application, the secondary 65 toggle link 11, is shown in Fig. 3 as having

operative association with the stem of a relief valve 27 arranged in a branch pipe of the pipe line connection between the air compressor and the inlet check valve of the storage reservoir of such compressed air apparatus. The arrangement is adapted to open said valve 27 and relieve said pipe line connection from pressure, as the present switch mechanism operates to open the circuit of the electric motor of the apparatus, 70 and so that in a subsequent starting of said electric motor there will be an absence of back pressure on the air compressor and in consequence an easy starting of the electric motor is assured.

Having thus fully described my said invention what I claim as new and desire to secure by Letters Patent, is:—

1. In an electric controller of the type herein described, the combination of a frame, a primary toggle link and a secondary toggle link pivoted to said frame with their pivots in adjacent relation, a spring having an elliptical form and attached at its respective ends to the toggle links aforesaid, a collar having operative engagement with the primary toggle link, a spring adapted to move said collar in one direction, and a power means adapted to move said collar in an opposite direction, substantially as set forth. 85

2. In an electric controller of the type herein described, the combination of a frame, an electric switch, a switch operating link, a primary toggle link, a secondary toggle link, the series of links being pivoted to said frame in adjacent relation and on an approximately common plane, the secondary toggle link having operative connection with the switch operating link aforesaid, a tension spring attached at its respective ends 90 to the toggle links aforesaid, a collar having operative engagement with the primary toggle link, a spring adapted to move said collar in one direction, and a power means for moving said collar in the opposite direction, 100 substantially as set forth. 105

3. In an electric controller of the type herein described, the combination of a frame, an electric switch, a switch operating link, a primary toggle link, a secondary toggle link, the series of links being pivoted to said frame in adjacent relation and on an approximately common plane, the secondary toggle link having operative connection with the switch operating link aforesaid by means 115 permitting limited independent movement between the parts, a tension spring attached at its respective ends to the toggle links aforesaid, a collar having operative engagement with the primary toggle link, a spring adapted to move said collar in one direction, and a power means for moving said collar in the opposite direction, substantially 120 as set forth. 125

4. In an electric controller of the type de- 130

- scribed herein, the combination of a frame, an electric switch, a switch operating link, a primary toggle link, a secondary toggle link, the series of links being pivoted to said frame in adjacent relation and on an approximately common plane, the secondary toggle link having operative connection with the switch operating link aforesaid by means permitting limited independent movement between the parts, means for adjusting the amount of said independent movement, a tension spring attached at its respective ends to the toggle links aforesaid, a collar having operative engagement with the primary toggle link, a spring adapted to move said collar in one direction, and a power means for moving said collar in the opposite direction, substantially as set forth.
5. In an electric controller of the type herein described, the combination of a frame, an electric switch, a switch operating link, a primary toggle link, a secondary toggle link, the series of links being pivoted to said frame in adjacent relation and on an approximately common plane, the secondary toggle link having a cross head formed with an enlarged orifice for the reception of switch operating link aforesaid and permitting limited independent movement between the parts, a tension spring attached at its respective ends to the toggle links aforesaid, a collar having operative engagement with the primary toggle link, a spring adapted to move said collar in one direction, and a power means for moving said collar in the opposite direction, substantially as set forth.
6. In an electric controller of the type herein described, the combination of a frame, an electric switch a switch operating link, a primary toggle link, a secondary toggle link, the series of links being pivoted to said frame in adjacent relation and on an approximately common plane, the secondary toggle link having operative connection with the switch operating link aforesaid by means permitting limited independent movement between the parts, means for adjusting the amount of said independent movement, the same comprising an abutment toe pivoted on the secondary toggle link and a screw for effecting a turning adjustment of the toe, a tension-spring attached at its respective ends to the toggle links aforesaid, a collar having operative engagement with the primary toggle link, a spring adapted to move said collar in one direction, and a power means for moving said collar in the opposite direction, substantially as set forth.
7. In an electric controller of the type herein described, the combination of a frame, an electric switch, a switch operating link, a primary toggle link, a secondary toggle link, the series of links being pivoted to said frame in adjacent relation and on an approximately common plane, the secondary toggle link having operative connection with the switch operating link aforesaid, a spring having an elliptical form and attached at its respective ends to the toggle links aforesaid, a collar having operative engagement with the primary toggle link, a spring adapted to move said collar in one direction, and a power means adapted to move said collar in the opposite direction, substantially as set forth. 75
8. In an electric controller of the type herein described, the combination of a frame, an electric switch, a switch operating link, a primary toggle link, a secondary toggle link, the series of links being pivoted to said frame in adjacent relation and on an approximately common plane, the secondary toggle link having operative connection with the switch operating link aforesaid by means permitting limited independent movement between the parts, a spring having an elliptical form and attached at its respective ends to the toggle links aforesaid, a collar having operative engagement with the primary toggle link, a spring adapted to move said collar in one direction, and a power means adapted to move said collar in the opposite direction, substantially as set forth. 80
9. In an electric controller of the type herein described, the combination of a frame, an electric switch, a switch operating link, a primary toggle link, a secondary toggle link, the series of links being pivoted to said frame in adjacent relation and on an approximately common plane, the secondary toggle link having operative connection with the switch operating link aforesaid by means permitting limited independent movement between the parts, means for adjusting the amount of said independent movement, a spring having an elliptical form and attached at its respective ends to the toggle links aforesaid, a collar having operative engagement with the toggle link, a spring adapted to move said collar in one direction, and a power means adapted to move said collar in the opposite direction, substantially as set forth. 95
10. In an electric controller of the type herein described, the combination of a frame, an electric switch, a switch operating link, a primary toggle link, a secondary toggle link, the series of links being pivoted to said frame in adjacent relation and on an approximately common plane, the secondary toggle link having operative connection with the switch operating link aforesaid by means permitting limited independent movement between the parts, means for adjusting the amount of said independent movement, a spring having an elliptical form and attached at its respective ends to the toggle links aforesaid, a collar having operative engagement with the toggle link, a spring adapted to move said collar in one direction, and a power means adapted to move said collar in the opposite direction, substantially as set forth. 100
11. In an electric controller of the type herein described, the combination of a frame, an electric switch, a switch operating link, a primary toggle link, a secondary toggle link, the series of links being pivoted to said frame in adjacent relation and on an approximately common plane, the secondary toggle link having operative connection with the switch operating link aforesaid by means permitting limited independent movement between the parts, means for adjusting the amount of said independent movement, a spring having an elliptical form and attached at its respective ends to the toggle links aforesaid, a collar having operative engagement with the toggle link, a spring adapted to move said collar in one direction, and a power means adapted to move said collar in the opposite direction, substantially as set forth. 105
12. In an electric controller of the type herein described, the combination of a frame, an electric switch, a switch operating link, a primary toggle link, a secondary toggle link, the series of links being pivoted to said frame in adjacent relation and on an approximately common plane, the secondary toggle link having operative connection with the switch operating link aforesaid by means permitting limited independent movement between the parts, means for adjusting the amount of said independent movement, a spring having an elliptical form and attached at its respective ends to the toggle links aforesaid, a collar having operative engagement with the toggle link, a spring adapted to move said collar in one direction, and a power means adapted to move said collar in the opposite direction, substantially as set forth. 110

Signed at Chicago, Illinois, this 7th day of June, 1917.

ORNE H. TORGERSEN.
